(57) **CLAIM**

The ornamental design for a dining table, as shown and described.

DESCRIPTION

FIG. 1 is a perspective view of a dining table, showing my new design;

FIG. 2 is a top plan view, showing an alternate environment; FIG. 3 is a bottom plan view, showing the environment in FIG. 1;

FIG. 4 is a top plan view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a perspective view showing a second embodiment of my new design;

FIG. 10 is a top plan view, showing an alternate environment;

FIG. 11 is a bottom plan view, showing the environment in FIG. 9;

FIG. 12 is a top plan view thereof;

FIG. 13 is a front elevational view thereof;

FIG. 14 is a rear elevational view thereof;

FIG. 15 is a right side elevational view thereof;

FIG. 16 is a left side elevational view thereof;

FIG. 17 is a perspective showing a third embodiment of my new design;

FIG. 18 is a top plan view, showing an alternate environment;

FIG. 19 is a bottom plan view, showing the environment in FIG. 17;

FIG. 20 is a top plan view thereof;

FIG. 21 is a front elevational view thereof;

FIG. 22 is a rear elevational view thereof;

FIG. 23 is a right side elevational view thereof; and,

FIG. 24 is a left side elevational view thereof.

The broken lines are for environmental purposes only and form no part of the claimed design.
